UNITED STATES PATENT OFFICE

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY

MANUFACTURE OF SHOES

Application filed January 11, 1930, Serial No. 420,251, and in Great Britain January 22, 1929.

This invention relates to the manufacture of shoes, and more particularly to the shaping of upper materials over lasts or other forms. The invention is herein illustrated in its application to the manufacture of shoes of the welt type, but it is to be understood that in various novel and useful aspects it is not thus limited in its applicability.

While it is the more common practice in the manufacture of various kinds of shoes, including welt shoes, to perform the side-lasting operation prior to the lasting of the toe and heel ends of the shoe, there have nevertheless been proposed and utilized heretofore to a considerable extent methods involving the shaping of at least the toe end portion of the upper materials (hereinafter referred to inclusively as the upper) to the contour required for the finished shoe prior to the lasting of the sides at the rear of the toe end. Such is the practice, for example, where the toe end portion of the upper is molded substantially in its final shape before the upper is mounted on a last. Likewise, in that process of shoe manufacture which involves the sewing of a welt to the shoe simultaneously with the lasting of its opposite sides, as disclosed in my earlier application Serial No. 325,839, filed on December 13, 1928, the final shaping or lasting of the toe end portion of the upper is preferably effected prior to the lasting of the sides at the rear of the toe.

It is an object of the present invention to provide a method of shoe making, including the shaping of the toe end portion of the upper prior to the lasting of the sides of the shoe, whereby the shaping of the toe portion will be effected under such conditions as to facilitate the later side-lasting operation and also to minimize any tendency for the previously shaped toe to be disturbed by the side-lasting operation or for that operation to be restricted in its effectiveness by reason of the previous shaping of the toe. For the purpose in view, as herein illustrated, the forepart of the upper at the rear of the toe is positioned and held in close conformity to the contour of the upper-shaping form or last during the shaping of the margin of the toe end portion of the upper as required for its

permanent attachment to an insole, after which the forepart at the rear of the toe is released and the side-lasting operation performed. In accordance with the procedure illustrated the upper at the rear of the toe is thus treated by pressure applied thereto over a continuous area including the hollow back of the toe and the top of the instep and also the opposite sides as far rearwardly as the ball of the shoe. It is a further characteristic of the procedure herein illustratively disclosed that a pull is applied to the toe end of the upper to tension the upper over the form before the portion at the rear of the toe is pressed against the form as above described. As a result of the close conformity of the forepart of the upper at the rear of the toe to the contour of the form at the time when the marginal portion of the upper around the toe is shaped as required for its permanent attachment to an insole, the marginal toe portion and the portion of the upper immediately at the rear of the toe are positioned in a relation to each other substantially as required for the finished shoe and tend to maintain substantially that relation thereafter, even though the margin of the forepart at the rear of the toe is left unfastened, as illustrated, until the side-lasting operation is performed. There is accordingly no undue tendency in the side-lasting operation to disturb the previously shaped margin of the toe end of the upper, nor is the effectiveness of the side-lasting operation in locations adjacent to the toe portion of the upper unduly restricted by the previously shaped toe. The method is herein disclosed as carried out by use of a last as the shaping form, the margin of the toe portion of the upper being shaped in lasted relation to an insole on the last, and is also disclosed as including the sewing of a welt on the shoe simultaneously with the side-lasting operations; but it is to be understood that in these and other respects the invention, in its more general aspects, is not limited to the illustrative disclosure.

The novel method will now be more particularly described by reference to the accompanying drawings and thereafter pointed out in the claims.

In the drawings,

Fig. 1 is a view partly in side elevation and partly in section, showing portions of a toe-lasting machine adapted for use in the practice of the novel method, this figure illustrating the tensioning of the upper over the last prior to the application of any substantial pressure to the forepart of the upper at the rear of the toe;

Fig. 2 is a view similar to Fig. 1, illustrating the pressing of the upper at the rear of the toe in close conformity to the contour of the last and the shaping of the margin of the upper about the toe in lasted relation to the insole;

Fig. 3 is a plan view of the means shown in Figs. 1 and 2 for pressing the upper at the rear of the toe closely about the last;

Fig. 4 is a view of a portion of the mechanism shown in Fig. 3 as it appears when viewed in the direction of the arrow shown on Fig. 1;

Fig. 5 is a perspective view of the toe portion of the shoe as it appears after it has been operated upon as illustrated in Figs. 1 and 2; and

Fig. 6 is a perspective view illustrating the later operation of lasting the opposite sides of the shoe and simultaneously sewing a welt to the upper and insole.

The machine illustrated in Figs. 1 and 2 for lasting the toe end of the shoe by the method of this invention is a machine of the same general character as that disclosed in Letters Patent No. 1,702,397 granted on February 19, 1929 upon an application of W. C. Baxter, and accordingly only such parts of the machine as it is necessary to refer to for an understanding of the invention are shown and will be described in detail. The machine is adapted to operate upon the toe portion of an upper loosely mounted on a last which is supported at its heel end on a spindle 10 and is further controlled by means of a heel rest 12, the spindle and heel rest being movable with the last in directions heightwise and lengthwise of the last, as more fully disclosed in the Letters Patent mentioned. For wiping the margin of the toe end portion of the upper inwardly into lasted relation to an insole *a* on the last, there are provided toe-embracing wipers 14, only one of which is seen in the drawings, and co-operating with these wipers are clamp members 16 which clamp the margin of the upper upon the top face of the wipers for the purpose of applying a pull to the toe end of the upper to tension the upper over the last. The machine herein shown is also provided with grippers 17, only one of which is seen in the drawings, for gripping the upper at the opposite ends of the tip line in the manner disclosed in Letters Patent No. 1,706,474, granted on March 26, 1929 upon an application of W. C. Baxter.

It will be understood that initially the last is

presented at a higher elevation and farther forwardly than illustrated in Fig. 1 and that after the clamping of the margin of the upper upon the wipers and by the grippers the last receives a rearward movement to subject the upper to a lengthwise pull, as also fully disclosed in Letters Patent No. 1,702,397. Thereafter the toe end of the insole *a* is engaged by a clamping plate 18 supported on a downwardly swinging arm 20 and its shank portion by a presser foot 21 also mounted on this arm, and by this means the last is depressed relatively to the wipers, clamp members and grippers for further tensioning the upper over the last. Fig. 1 illustrates the positions of the parts at the end of this downward movement of the last, the toe end of the shoe at this time being pressed downwardly upon a toe rest 22 which in the construction herein shown is mounted in a fixed position upon a toe rest support 24.

For pressing the forepart of the upper in close conformity to the contour of the last at the rear of the toe, the machine herein shown is provided with a fluid-pressure device comprising an inflatable rubber pad 26 supported upon a casing 28 which is mounted on the toe rest support 24 in a manner hereinafter described. The casing 28 and the pad 26 are of such form and dimensions as to embrace the upper and last at the rear of the toe and to extend rearwardly over the high part of the instep and along the sides of the last as far as the ball of the shoe. The casing 28 is pivotally supported at its front end on a pin 30 mounted in a block 32 (Fig. 4) which is mounted to turn about a pin 34 at right angles to the pin 30, so that a substantially universal joint is provided between the casing and its support 24. The casing 28 is permitted to rock laterally about the pin 30 to adjust itself to the swing of different lasts, and for controlling such movement there are provided leaf springs 36 arranged to bear respectively on the opposite side portions of the casing to centralize it when there is no last in the machine. For determining the position of the casing 28 in respect to movement about the pin 34, there is provided a member 38 having a ball-shaped end positioned in a socket formed in the casing, the member 38 being adjustable to vary the position of the casing, as may be required for shoes of different shapes or sizes.

For expanding or inflating the pad 26 to apply pressure to the upper, it is contemplated that there will be provided a suitable pump and reservoir for compressed air (not herein shown), although it is to be understood that the utility of the upper-pressing means does not depend upon the use of fluid of that particular character. Leading from the compressed air supply to a valve 40 is a pipe 42, and leading from the valve to the pad 26 is a pipe 44. The valve 40 herein shown is a

hand-operated valve controlled by a hand lever 46 (Fig. 3). It will be understood that when the valve 40 is in the position illustrated in Fig. 2 the pipes 42 and 44 are in communication with each other through a peripheral recess in the valve, and that when the valve is in the position shown in Fig. 1 this communication is interrupted and the pipe 44 is connected to the atmosphere through an opening 48 in the valve.

It will be understood that in the downward movement of the last hereinbefore described it is carried into the recess provided by the casing 28 and the pad 26, but no substantial pressure is applied to the upper by the pad until after the parts have arrived in the positions illustrated in Fig. 1, as will be evident by reference to the cross-sectioned portion of the pad and adjacent shoe and last parts in that figure. With the parts of the machine thus positioned and the machine preferably at rest, the operator manipulates the valve 40 to admit compressed air to the pad, whereupon the pad is expanded and presses the upper in close conformity to the contour of the last. It will be observed that such pressure is applied over a continuous area including the hollow back of the toe and the top of the instep and extending also over the sides of the last nearly as far as the edge of the last bottom and as far rearwardly as the location of the ball of the shoe. The pressure is accordingly applied by the pad to substantially all portions of the forepart of the upper at the rear of the toe. After the pressure has thus been applied, the machine is again started and the wipers 14 are operated to wipe the margin of the upper inwardly over the insole around the end and along the sides of the toe to its final lasted position, as illustrated in Fig. 2, the clamp members 16 preferably continuing to press the margin of the upper upon the wipers during a portion, at least, of this operation to render them more effective to pull the upper tightly over the last and insole. Near the end of the wiping operation the clamp members are lifted and the grippers 17 also opened. During this operation the forepart of the upper at the rear of the toe is maintained in close conformity to the contour of the last by the pressure pad, which in addition to its conforming action serves to hold the upper in that location against loss of such tension as it received from the pull of the clamping and gripping means thereon while also assisting in supporting the last.

The parts shown in Figs. 1 and 2 include a trimming knife 50 movable to trim the margin of the upper flush with the upper face of the wipers 14 in the same manner as disclosed in Letters Patent No. 1,702,397. It will be understood that after removing the shoe from the machine the operator will detach the opposite ends of the strip of waste material from the remainder of the upper,

so that the toe portion of the shoe will appear as indicated in Fig. 5. Preferably the machine will come to a stop at the end of the upper-trimming operation, and the operator may then, if desired, insert a fine wire staple 70 to fasten the upper to the lip of the insole at each end of the tip line, although the invention is not limited to the fastening of the upper in this location or in this manner. As illustrated, the forepart of the upper at the rear of the toe is left in an unfastened condition. The pause in the operation of the machine at this point will also enable the operator to release the air pressure from the pad 26, so that when the arm 20 is raised the pad will not be unduly expanded.

If, as preferred, the upper has received no previous shaping over the last prior to the lasting of the toe, as above described, the heel-end portion of the shoe may next be lasted, for example by means of a machine of the type disclosed in Letters Patent No. 1,583,044, granted on May 4, 1926 upon an application of C. H. Hoyt. In such a machine the margin of the heel-end portion of the upper materials will be wiped inwardly over the insole and will be secured by lasting tacks 80 (Fig. 6).

Although, as hereinbefore suggested, the invention in its more general aspects is not limited in respect to the character of the side-lasting operation, in accordance with the procedure herein illustrated the shoe is next presented to a machine of the type disclosed in my earlier application, whereby the opposite side portions of the upper are lasted progressively and in the same operation a welt is sewed to the upper and insole, as illustrated in Fig. 6. A machine of that type includes a gripper 52 for gripping and pulling the upper in each successive lasting location, a channel guide 54 for engaging the lip of the insole to position and guide the shoe, a welt guide 56, a wiper 58, a needle 60 and a looper 62, all operating in the manner disclosed in that application. It will be understood that the operation of the machine on the shoe will begin in a location adjacent to the heel breast line at one side of the shoe, and will progress along that side of the shoe and around the toe and then along the other side of the shoe rearwardly to the heel breast line. It will be further understood that in operating around the toe the gripper 52 will be rendered inoperative, so that the only operation performed will be the sewing of the welt to the previously lasted and trimmed upper. After these operations have been performed the manufacture of the shoe will be completed in any suitable well-known manner.

It will thus be seen that by this invention a method is provided whereby the shaping of the toe-end portion of the upper prior to the side-lasting of the shoe is performed under such conditions as to facilitate the later side-

lasting operation and to insure that the effectiveness of that operation will not be unduly restricted by the previously shaped or lasted toe and also to insure against any undue tendency for the side-lasting operation to disturb on the last the position of the previously shaped toe. That is to say, with the margin of the toe-end portion of the upper shaped under the conditions described, the forepart of the upper at the rear of the toe is thereafter positioned in such relation to the last and to the previously shaped toe that there is but little looseness to be taken up in the side-lasting of that portion of the upper and, therefore, no need in that operation for subjecting the upper to anything more than very localized and restricted tensions.

Novel features of the machine herein shown and described are claimed in a divisional application, Serial No. 542,853, filed on June 8, 1931.

Having described the invention, what I claim as new and desire to secure by Letters Patent of the United States is:

1. That improvement in methods of making shoes which consists in pressing an upper at the rear of the toe in close conformity to the contour of a form in the hollow back of the toe and rearwardly along the instep and also rearwardly along the sides of the form as far as the ball of the shoe and while holding it thus under pressure shaping the margin of its toe end portion over the form, releasing the upper from the pressure thus applied, and thereafter lasting the sides of the shoe at the rear of the toe.

2. That improvement in the methods of making shoes which consists in pressing an upper at the rear of the toe in close conformity to the contour of a form over a substantially continuous area extending over the top of the form in the hollow back of the toe and rearwardly along its opposite sides as far as the ball of the shoe and while holding it thus under pressure shaping the margin of its toe end portion over the form as required for permanent attachment to an insole, releasing the upper from the pressure thus applied, and thereafter lasting the sides of the shoe at the rear of the toe.

3. That improvement in methods of making shoes which consists in conforming an upper at the rear of the toe to the contour of a form in the hollow back of the toe and rearwardly along the instep and while holding it thus conformed with the margin of its forepart at the rear of the toe in an unfastened condition shaping the margin of its toe end portion over the form, releasing the upper at the rear of the toe with the margin of its forepart still unfastened in that location, and thereafter lasting the sides of the shoe at the rear of the toe.

4. That improvement in methods of mak-

ing shoes which consists in conforming substantially the entire forepart of an upper at the rear of the toe to the contour of a form and while holding it thus conformed with its margin in that location in an unfastened condition shaping the margin of its toe end portion over the form as required for permanent attachment to an insole, releasing the forepart of the upper at the rear of the toe with its margin still unfastened in that location, and thereafter lasting the sides of the shoe at the rear of the toe.

5. That improvement in methods of making shoes which consists in pressing an upper at the rear of the toe in close conformity to the contour of a form in the hollow back of the toe and rearwardly along its opposite sides as far as the ball of the shoe and while holding it thus under pressure with the margin of its forepart at the rear of the toe in an unfastened condition shaping the margin of its toe end portion over the form, releasing the upper at the rear of the toe from the pressure thus applied with the margin of its forepart still unfastened in that location, and thereafter lasting the sides of the shoe at the rear of the toe.

6. That improvement in methods of making shoes which consists in pressing an upper at the rear of the toe in close conformity to the contour of a form over a substantially continuous area extending across the top of the form in the hollow back of the toe and rearwardly along the sides of the form as far as the ball of the shoe and while holding it thus under pressure shaping the margin of its toe end portion over the form as required for permanent attachment to a welt shoe insole, releasing the forepart of the upper from said pressure, and thereafter lasting the opposite sides of the shoe progressively and in the same operation fastening a welt to the shoe.

7. That improvement in methods of making shoes which consists in conforming substantially the entire forepart of an upper at the rear of the toe to the contour of a form and while holding it thus conformed with its margin in that location in an unfastened condition shaping the margin of its toe end portion over the form as required for permanent attachment to a welt shoe insole, releasing the forepart of the upper at the rear of the toe with its margin still unfastened in that location, and thereafter lasting the opposite sides of the shoe progressively and in the same operation fastening a welt to the shoe.

8. That improvement in methods of making shoes which consists in applying a pull to the toe end of an upper to tension the upper over a form and then while holding it under tension pressing the upper at the rear of the toe in close conformity to the contour of the form in the hollow back of the toe and

- along the instep and also rearwardly along its opposite sides as far as the ball of the shoe, shaping the margin of the toe end portion of the upper over the form while maintaining the pressure thus applied at the rear of the toe, releasing the upper from said pressure after the shaping of the margin of its toe end portion, and thereafter lasting the sides of the shoe at the rear of the toe. 5 70
10. That improvement in methods of making shoes which consists in applying a pull to the toe end of an upper to tension the upper over a form and then while holding it under tension pressing the upper at the rear of the toe in close conformity to the contour of the form over a substantially continuous area extending over the top of the form in the hollow back of the toe and rearwardly along the opposite sides of the form, shaping the margin of the toe end portion of the upper over the form while maintaining the pressure thus applied at the rear of the toe with the margin of the forepart at the rear of the toe in an unfastened condition, releasing the upper from said pressure with the margin of its forepart at the rear of the toe still unfastened, and thereafter lasting the sides of the shoe at the rear of the toe. 15 75
11. That improvement in methods of making shoes which consists in applying a pull to the toe end of an upper to tension the upper over a form and then while holding it under tension conforming substantially the entire forepart of the upper at the rear of the toe to the contour of the form, shaping the margin of the toe end portion of the upper over the form as required for permanent attachment to an insole while maintaining the forepart at the rear of the toe in conformity to the contour of the form with its margin in that location in an unfastened condition, releasing the forepart of the upper at the rear of the toe with its margin still unfastened in that location, and thereafter lasting the sides of the shoe at the rear of the toe. 20 80
12. That improvement in methods of making shoes which consists in applying a pull to the toe end of an upper to tension the upper over a last and then while holding it under tension conforming the forepart of the upper at the rear of the toe to the contour of the form, thereafter without releasing the toe portion of the upper from the tension previously applied shaping its margin over the form while maintaining the forepart of the upper at the rear of the toe in conformity to the contour of the form with its margin in that location in an unfastened condition, releasing the forepart of the upper at the rear of the toe with its margin still unfastened in that location, and thereafter lasting the sides of the shoe at the rear of the toe. 25 85
13. That improvement in methods of making shoes which consists in pressing an upper at the rear of the toe in close conformity to the contour of a last over a substantially continuous area extending across the top of the last in the hollow back of the toe and rearwardly along its opposite sides as far as the ball of the shoe and while holding it thus under pressure shaping the margin of its toe end portion in lasted relation to an insole on the last, releasing the forepart of the upper from the pressure thus applied, and thereafter lasting the sides of the shoe at the rear of the toe. 30 90
14. That improvement in methods of making shoes which consists in conforming substantially the entire forepart of an upper at the rear of the toe to the contour of a last and while holding it thus conformed with its margin in that location in an unfastened condition shaping the margin of its toe end portion in lasted relation to an insole on the last, releasing the forepart of the upper at the rear of the toe with its margin still unfastened in that location, and thereafter lasting the sides of the shoe at the rear of the toe. 35 95
15. That improvement in methods of making shoes which consists in applying a pull to the toe end of an upper to tension the upper over a last and then while holding it under tension pressing the upper at the rear of the toe in close conformity to the contour of the last in the hollow back of the toe and along the sides of the last as far as the ball of the shoe, lasting the toe end of the upper over an insole on the last while holding it at the rear of the toe under the pressure thus applied, releasing the upper from said pressure after the lasting of the toe, and thereafter lasting the sides of the shoe at the rear of the toe. 40 100
16. That improvement in methods of making shoes which consists in applying a pull to the toe end of an upper to tension the upper over a last and then while holding it under tension conforming the forepart of the upper at the rear of the toe to the contour of the top and sides of the last with its margin in an unfastened condition, there- 45 105

after without releasing the toe portion of the upper from the tension previously applied shaping its margin in lasted relation to an insole on the last while maintaining the forepart at the rear of the toe in conformity to the contour of the last, releasing the forepart of the upper at the rear of the toe with its margin still unfastened in that location, and thereafter lasting the sides of the shoe at the rear of the toe.

10 17. That improvement in methods of making shoes which consists in applying a pull to the toe end of an upper to tension the upper over a last and then while holding it under tension conforming substantially the entire forepart of the upper at the rear of the toe to the contour of the last, shaping the margin of the toe end of the upper in lasted relation to a welt shoe insole on the last

15 20 while holding the forepart at the rear of the toe thus conformed to the last with its margin in an unfastened condition, releasing the forepart of the upper at the rear of the toe with its margin still unfastened in that location,

25 25 and thereafter lasting the sides of the shoe at the rear of the toe progressively and in the same operation fastening a welt to the shoe.

In testimony whereof I have signed my name to this specification.

ARTHUR BATES.
